CAFETERIA TABLE APPLIANCE

Harry C. Gessler, Brooklyn, N. Y.

Application January 6, 1933, Serial No. 650,410

10 Claims. (Cl. 65—5)

This invention relates to table appliances for cafeterias.

One object of the invention is to provide an appliance of the character described wherein a plurality of devices such as a tray and a napkin dispenser are coordinated in improved association with each other.

In cafeterias, especially, where a considerable number of patrons may be seated at one table, the table space is relatively limited and crowded, and hence to economize in available room, it has been customary to provide a centrally located tray elevated above the table. Such tray is used for containers for sugar, mustard, spices, and the like, which are thus accessibly located, easily seen, do not occupy any table space, and moreover, do not interfere with the cleaning of the table. In other words, when the dishes are removed by the attendants from the table, the latter is uniformly free and vacant. A napkin dispenser, however, is generally positioned on the table, and this is the only device thereon which is constantly located on the table and which militates against the uniformly free and unencumbered condition of the cleared table, besides occupying space and being in the way when the table is in use by the patrons. This drawback, which I have perceived, I have remedied by the invention herein described.

Another object of the invention is to furnish an appliance of the nature set forth, wherein the tray which is normally mounted on a suitable pedestal has improved association with said pedestal and the napkin dispenser so as to be interchangeably mounted on either, according to the requirements of the particular cafeteria.

More specifically, some cafeterias have a single source of supply of the napkins, to which the patrons must go for their napkins, and in such cases the cafeteria may prefer to have the trays mounted on the pedestals. Hence it will be of considerable advantage to the manufacturer to provide an appliance wherein the tray is interchangeably connected with the napkin dispenser and the pedestal. Moreover, the cafeteria may purchase such appliances and consequently use the tray and pedestal combination or the tray and napkin dispenser combination as may be preferred or as exigencies may require.

A further object of the invention is to provide an appliance of the type mentioned having few and simple parts, and which is inexpensive to manufacture and assemble, and durable, convenient, reliable, and efficient in use, and neat in appearance.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Figure 1 is a view in front elevation with parts in section showing an appliance embodying the invention.

Fig. 2 is a view in front elevation of an appliance embodying the invention according to a different combination thereof.

Fig. 3 is a view in side elevation of a napkin dispenser according to the invention.

Fig. 4 is a top plan view on a reduced scale of the device shown in Fig. 1.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Referring in detail to the drawing, 10 denotes an appliance embodying the invention. The same includes a conventional napkin dispenser 11 and any suitable tray 12 mounted thereon so as to extend over the said dispenser.

The invention may also include an appliance having the napkin dispenser 11, tray 12, and any support or pedestal 13 so associated that the tray 12 may be interchangeably mounted on the dispenser and pedestal to produce a device 10a which illustrates a second phase of the appliance, of which the device 10 may be considered the first phase.

14 denotes a conventional cafeteria table upon which the appliance 10 or 10a may be mounted or attached in central relation, so that there is a maximum substantially uniform space between the periphery 15 of the said table and the dispenser 11 or pedestal 13 as the case may be.

For the purpose of illustrating one form of the invention, it will be sufficient to indicate that the napkin dispenser 11 includes a casing 16 having

50

55

side walls 17, a front wall 18, a rear wall 19, and a top wall 20. Said casing may be weighted at its base by a plate 21. Within the casing, a feeder such as a plate 22 may be provided, actuated toward the front wall by an actuator such as an expansion coil spring 23. The front wall 18 may have an opening 24 smaller in size than the plate 22 so as to assure retention of the latter. Formed in the sides 17 of the casing are openings 25 located near the front wall. Secured substantially centrally on the top of the casing is a holding means of any well known type, such as a pin or stud 26 which may be suitably covered when not in use, as by a cap 27 threadedly connected thereto.

It will suffice briefly to point out that napkins such as paper napkins are thrust into the casing through opening 24 so that the edge portions of the napkins are engaged behind the front wall 18, the plate 22 being simultaneously rearwardly moved compressing the spring 23. The latter assures a constant forward feed of the napkins against the wall 18, as the napkins are successively removed by grasping an outermost napkin at a small outward fold 28 therein so as to pull the napkin out through the opening 24. When the supply of napkins in the casing runs low, that condition can be observed through an opening 25. The napkin dispenser herein described is of a conventional type except for the holding means 26 and openings 25, and any other kind of napkin dispenser, of different construction and mode of operation may be substituted therefor.

The tray 12 may be of any well known shape and construction, and includes, generally, a bottom plate 29 and a marginal flange 30. Substantially centrally connected to the bottom plate 29 in downward acting relation, and in stationary or rotary association with said bottom plate, is a holding means of a conventional type adapted for engagement with the upper part of the dispenser 11. Said holding means may include a socket element 31 that may have a pin 32 on which the tray is journaled. The socket element is adapted for threaded engagement with the stud 26 so that the tray will be mounted on the napkin dispenser in central relation thereto as shown.

The pedestal 13 may be of any well known type, and may include a weighted base 33 or other holding means. At its upper end, the pedestal may have a holding means of any suitable type, as, for illustration, a threaded projection or stud 26a similar to 26 so as to be engageable in the socket element 31, whereby the tray can be carried by the pedestal.

It will thus be seen that the invention provides an appliance including a napkin dispenser, a tray and a pedestal, which are interchangeably associated in a reliable manner to provide practical devices 10 and 10a. Hence the manufacturer and cafeteria need carry fewer parts, and may provide either device 10 or 10a as may be necessary.

In the device 10, the napkin dispenser as a whole may act as a weighting means for holding the tray in a stable manner, and need not occupy any more table space than that required by the base of the pedestal. The tray may be used in the usual convenient manner. The supply of napkins can be observed through opening 25, so that the dispenser need not be removed from the table or otherwise manipulated for filling the same.

If the napkin dispenser is to be separately used,

the tray is detached, and the cap 27 secured to afford a uniform neat appearance for the device, whereby a still different form of the invention is obtained.

I claim:

1. A device including a vertically elongated portable casing having a top wall and a side wall, the latter having an opening for removably receiving napkins, said top wall having an upwardly projecting element, and a horizontal tray having a central downwardly extending element, said elements constituting removably interengaging male and female members.

2. A cafeteria appliance including a napkin dispenser casing having top and bottom walls and a side wall provided with an opening of substantial size for removably receiving napkins, and a horizontal tray, said casing having an upwardly extending screw element at said top wall, and said tray having a downwardly extending female portion internally threaded for removable connection with the screw element.

3. A device including a vertically elongated portable napkin dispenser casing having a top and bottom wall and a side wall provided with a similarly elongated opening for removably receiving napkins, and a horizontal tray, said casing having an upwardly extending element engaged with said top wall, and said tray having a downwardly extending element secured thereto, said elements constituting removably interengaging male and female members for supporting the tray.

4. A cafeteria table appliance including a napkin dispenser casing, the same having a top wall and a side wall, the latter having an opening for removably receiving napkins, and an element of male and female releasably interengaging elements for mounting a horizontal tray over said casing, said elements being mounted on said casing in engagement with said top wall.

5. A device including a vertically elongated portable casing having a top wall and a side wall, the latter having an opening for receiving napkins, said top wall having an upwardly projecting screw element, and a horizontal tray having a central downwardly extending sleeve internally threaded for removable connection with the screw element.

6. A cafeteria table appliance including a napkin dispenser casing having top and bottom walls and a side wall provided with an opening for removably receiving napkins in the casing, and a horizontal tray, said casing and tray having male and female releasably interengaging elements disposed so as to mount the tray over the casing.

7. A cafeteria table appliance including a napkin dispenser casing having top, bottom walls and side walls interconnected to brace each other, one of the side walls having an opening for removably receiving napkins in the casing, a horizontal tray overlying the casing, and releasably interengaging male and female elements, one of said elements being connected to the tray, and the other element being connected to the casing so as to be laterally reinforcing held by the latter.

8. A cafeteria table appliance including a napkin dispenser casing of box construction of the type that is light in weight, said casing having thin walls interconnected for mutually bracing each other, one of the walls having a side opening for removal of napkins in the casing, and a horizontal tray having a radially continuous

bottom wall overlying the casing and the casing and tray having interengaging connecting means so that the tray is reliably supported by the box construction of the casing.

- 5 9. A portable cafeteria table appliance including a napkin dispenser casing of box construction of the type that is held in position by a base weight, said casing having thin walls interconnected with each other, one of the walls having a side opening for removably receiving napkins in the casing, and a horizontal tray having a disc shaped bottom wall overlying the casing and the latter and the tray having interengaging connecting means positioned remotely from the 10 edges of the tray so that the tray is maintained as a movable unit with the casing.
- 10 15. A portable cafeteria table appliance includ-

ing a napkin dispenser casing of box construction of the type that is held in position by a weight at the base thereof, said casing having thin walls interconnected with each other, one of the walls having a side opening for removably receiving napkins in the casing and a horizontal tray having a disc shaped bottom wall overlying the casing and the latter and the tray having detachably engaged connecting means located 5 remotely from the edge of the tray so that the same is normally maintained as a movable unit with the casing, and the latter being complete and adapted to function as a napkin dispenser in the detached condition thereof with respect to the tray.
